UNITED STATES PATENT OFFICE

EMIL PFIFFNER, OF BUDAPEST, HUNGARY

ARRANGEMENT FOR REDUCING THE STRAY REACTANCE OF CASCADE TRANSFORMERS

Application filed November 26, 1923, Serial No. 677,114, and in Germany November 28, 1922.

This invention relates to improvements in arrangements for reducing the leakage reactance of compound or cascade transformers and essentially consists in the provision of 5 compensating windings which convey and improve the electromagnetic interlinking between the primary and secondary windings and the coupling windings respectively.

With the above object in view the invention consists of certain novel details of construction hereinafter fully described and claimed.

Several modes of carrying out the present invention are illustrated by way of example 15 on the accompanying sheets of drawings in which:—

Fig. 1 shows diagrammatically a compound or cascade transformer constructed according to the present invention.

20 Figs. 2 and 3 illustrate the constructive arrangement of compensating or equalizing windings.

Figs. 4 and 5 illustrate in sectional elevation and plan view respectively a compound 25 or cascade transformer constructed according to the present invention.

As shown in Fig. 1 the compound or cascade transformer comprises a number of individual transformers connected in series.

30 By placing a number of such transformers one on the other a transformer for any voltage can be constructed. It is well known that such an arrangement has the advantage of simplification of manufacture by using the same coil elements for construction of apparatus for the most varied voltages.

There is, however, the disadvantage that owing to differences in the magnetic resistance of the separate cores and the reaction of 40 the secondary windings in the coils of the different cores different voltages are induced which affects the accuracy of the secondary windings.

45 Owing to the magnetic leakage at the ends of the core inequalities occur in the magnetic flux of the iron core; this is very undesirable.

The object of this invention is to overcome 50 these objections by means of compensating coils which are connected up in opposition to

each other and compensate any variation in the magnetic flux occurring in the coils.

The other undesirable objection of inequalities in the magnetic flux of the iron core is overcome by the arrangement of a further 55 compensating winding. This winding comprises two coils connected in opposition to each other, and arranged at the points of the magnetic circuits which are to be mutually compensated.

Owing to the better electric insulation cascade transformers are employed as high-tension transformers particularly voltage-transformers, the said cascade transformers comprising a number of individual transformers connected in series, each of the latter being constructed and insulated for a part 60 of the voltage. Each of these individual transformers is provided with a high-tension winding W_1, W_2, W_3 through which the respective individual voltage is adapted to pass and which is in series with the other individual transformers. The beginning of winding of the first individual transformer is connected to the respective high-tension line and the 65 end of winding is grounded. In order to attain the smallest insulation-stress, the iron members of the individual transformers are constructively connected with the centre of winding of the respective part-members. The 70 grounded secondary winding s lies next to the high-tension coil which is grounded.

The voltage drop between the individual 75 transformers is increased uniformly and therefore the secondary winding, whose voltage drop is very small compared with the drop in the high-tension winding or which may be considered as having the same potential throughout, cannot be arranged with respect to the high-tension winding in the manner of two hollow cylinders disposed within 80 one another, as otherwise the whole of the high-tension winding would have to be insulated against earth connection. However, 85 also the electromagnetic reaction of the secondary current has to be transferred to all individual transformers. This cannot be accomplished by series connection of all secondary windings, as otherwise all individual high-tension windings would require to be 90 100

entirely insulated against earth connection and thus the entire compound or cascade arrangement would be of no use. Moreover the transfer of the secondary reaction has to be accomplished by means of coupling windings, which electromagnetically couple the upper end of one member with the lower end of the adjacent member.

As shown in Fig. 1, W_1 , W_2 , W_3 designate the high-tension windings. W_1 , W_2 , W_3 of the transformer are connected to the iron cores f_1 , f_2 , f_3 by means of connections U_1 , U_2 , and U_3 .

The coupling windings K_1'' and K_2' and K_2'' and K_3' respectively are connected in opposition. Their effects result therefrom, that the secondary windings s of the flux in the iron-core f_1 is weakened, whereby a smaller tension is induced than in the winding K_2' , so that a compensating or equalizing current will be produced from the windings K_2' to the winding K_1'' , which has the tendency to increase the flux in the iron core f_1 and to reduce the flux in the iron-core f_2 .

The weakening in the iron-core f_2 will produce the same effect in the iron-core f_3 over the coupling windings K_2'' and K_3' , and thus the reaction of the secondary current is transferred to all members.

From the above it is clear, that the principle of construction of these compound or cascade transformers will lead to an axially displaced arrangement of primary and secondary windings, thus to a construction which does not produce a good electromagnetic interlinking of these windings but a large leakage resistance. Therefore in practice the arrangement diagrammatically illustrated in Fig. 1 is of no use, as during a secondary stress it will yield voltage drops which are far too large. These reactive drops produce an unsymmetrical distribution of the magnetic flux in the magnetic iron in such a manner that the flux is reduced in the direction of current along the axis of magnetic cores.

The arrangement hereinafter described reduces the leakage to a tolerable degree by arranging on the iron-core a compensating or equalizing winding a' , a'' , which by means of a direct electrical connection with the same is brought to the same electrical potential and which is disposed concentrically with respect to the primary and secondary winding as diagrammatically shown in Fig. 2.

The said compensating or equalizing winding consists of two coils which are connected in opposition and try to prevent the unsymmetrical field distribution produced by the compensating current during the field displacement. By this arrangement the entire drop of stay or leakage is reduced to a tolerable degree and the cascade arrangement may be used for measuring purposes.

Fig. 3 illustrates diagrammatically the

constructive arrangement of the compensating or equalizing winding a' , a'' . The iron-core f may be used as one of the two connections of the coils a' , a'' .

In the arrangement illustrated in Fig. 3 the best possible electromagnetic interlinking of the three windings is conclusive for the arrangement of the three windings with respect to one another.

Fig. 4 shows in longitudinal section a two stage cascade transformer provided with the various windings above described. Fig. 5 is a cross-sectional view of the transformer shown in Fig. 4 and illustrates the arrangement of the windings W_1 , and the iron-core f_1 . W_1 and W_2 designate the two series-connected high-tension windings to which are coaxially coupled the oppositely connected coupling windings k_1' and k_1'' . The coupling winding k_1' of the top unit is disposed at the bottom end of the winding w_2 , while the coupling winding k_1'' of the bottom unit is located at the top end of the winding w_1 . The secondary winding s is disposed at the bottom end of the winding w_1 .

These windings are insulated by an insulating sleeve from the concentrically arranged compensating or equalizing windings a' and a'' of the bottom unit and a_1' and a_1'' of the top unit. The said compensating windings possess small induced tensions only and therefore need to be slightly insulated only with respect to the iron-cores f_1 and f_2 respectively, so that the latter can be used as electric return line connection.

The centres of the high-tension windings W_1 and W_2 are connected with the iron-cores f_1 and f_2 by means of connections u_1 and u_2 , in order to determine the maximum tension of the insulating sleeve between the high-tension windings and the iron-cores.

The operative parts of the two series-connected units are mounted in insulating cases b_1 and b_2 , which are cemented to the sleeves h . The bottom unit rests on an earthed base g in which are mounted secondary terminals. A hood c provided with a terminal d for the high tension line, is mounted on the top unit. Fig. 5 shows the relative arrangement of the iron-core f_1 and the winding W_1 in the insulating case b_1 .

I claim:

1. In a cascade transformer, a plurality of iron cores, a plurality of series connected high tension primary windings inductively wound with said cores, each being electrically connected to the middle point of its respective core, a secondary winding, coupling windings axially displaced with respect to one another to effect an equalization of the magnetic flux in said cores and compensating windings each consisting of two coils arranged on the same iron core acting in opposite directions and connected in opposition whereby the leakage reactance of said transformer is reduced.

2. In a cascade transformer, a plurality of iron cores, a plurality of series connected high tension primary windings inductively wound with said cores each being electrically connected to the middle point of its respective core, a secondary winding, coupling windings axially displaced with respect to one another to effect an equalization of the magnetic flux in said cores and compensating windings comprising a pair of oppositely wound coils on the same iron, said iron core forming a connecting link between said coils, whereby the leakage reactance of said transformer is reduced.

15 In testimony whereof I hereunto affix my signature.
